US0D1021384S

(12) United States Design Patent (10) Patent No.: US D1,021,384 S
(45) Date of Patent: * Apr. 9, 2024

(54) BAG

(71) Applicant: Color Maple Ltd., Kowloon (HK)

(72) Inventor: Darshan Parekh, Hong Kong (HK)

(73) Assignee: Color Maple Ltd., Kowloon (HK)

() Term: 15 Years

(21) Appl. No.: 29/812,965

(22) Filed: Oct. 26, 2021

(51) LOC (14) Cl. 03-01

(52) U.S. Cl.

(57) CLAIM

The ornamental design for a bag, as shown and described.

DESCRIPTION

FIG. 1 is a top perspective view of a bag according to the present design.

FIG. 2 is a bottom perspective view of the bag shown in FIG. 1.

FIG. 3 is a front elevation view of the bag shown in FIG. 1.

FIG. 4 is a rear elevation view of the bag shown in FIG. 1.

FIG. 5 is a top plan view of the bag shown in FIG. 1.

FIG. 6 is a bottom plan view of the bag shown in FIG. 1.

FIG. 7 is a left side elevation view of the bag shown in FIG. 1; and,

FIG. 8 is a right side elevation view of the bag shown in FIG. 1.

The broken lines illustrate portions of the bag that form no part of the claimed design.

1 Claim, 8 Drawing Sheets
